(57) **CLAIM**

The ornamental design for a display screen or portion thereof with animated icon, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with animated icon showing the claimed design;

FIG. 2 is a front view of a second image thereof; and,

FIG. 3 is a front view of a third image thereof.

The peripheral dashed broken lines illustrate a display screen or portion thereof, and form no part of the claimed

(Continued)

design. The appearance of the icon transitions sequentially between the images shown in FIGS. 1-3.

1 Claim, 1 Drawing Sheet
